UNITED STATES PATENT OFFICE.

CHARLES LATHAM, OF DETROIT, MICHIGAN.

WINDOW-CURTAIN STRETCHER.

1,296,297.

Specification of Letters Patent.

Patented Mar. 4, 1919.

Application filed September 24, 1918. Serial No. 255,461.

To all whom it may concern:

Be it known that I, CHARLES LATHAM, a citizen of the United States, residing at Detroit, in the county of Wayne and State of Michigan, have invented certain new and useful Improvements in Window-Curtain Stretchers, of which the following is a specification.

This invention is a window curtain stretcher and has for its principal object the production of a frame so constructed as to stretch the curtains after the same has been washed or to retain curtains in a stretched condition when in use in connection with a window, causing the curtains to be evenly retained at all times, and thus present a pleasing appearance.

Another object of this invention is the production of a curtain stretcher or support which consists of a frame of an adjustable nature, thus allowing the device to be used in connection with curtains and windows of various sizes.

Another object of this invention is the production of a window curtain stretcher wherein a plurality of telescopic tubes are provided and are connected together to form a rectangular frame of an adjustable nature.

One practical form of construction and assembly of the present invention will be hereinafter described and is illustrated in the drawing, in which—

Figure 1 is a front elevation of the window curtain stretcher.

Fig. 2 is a side elevation of the device.

Fig. 3 is an enlarged sectional view of the device taken on the line 3—3 of Fig. 1.

Fig. 4 is a longitudinal section through the telescoping tubes illustrating the manner in which the same engage each other, and

Fig. 5 is a fragmentary sectional view illustrating the connection between one of the uprights and one of the horizontal tubes of the device.

In the preferred embodiment of the present invention about to be described, it will be seen that 10 designates a window frame, upon which the device is to be carried when used for supporting curtains in a stretched condition to prevent the same from wrinkling and also to cause the curtains to present a pleasing appearance, although it is obvious the frame may be employed for stretching the curtains after the same are washed.

The horizontal supporting members comprise primary tubes 11 and auxiliary tubes 12, the tubes 12 telescoping within the primary tubes 11. The tubes 11 are provided with clamping bands 13 adjacent their ends, thus holding the tubes 12 by frictional engagement against tendency of accidental slipping when in use. The tubes 11 and 12 are provided with ends 14 bent to extend at right angles thereto and having clamping rings 15 engaging the sleeves 16 extending into the ends 14 and carrying wall plates 17. Thus it will be seen that the wall plates 17 may be fixed upon a window frame 10 and retain the major portions of the horizontal supporting members spaced from the window frame.

In order to reinforce the horizontal supporting members intermediate their ends 75 brackets 18 are connected to the window frame 10 and have set screws 19 for bearing upon the tubes and holding the same in set position as illustrated in Figs. 1 and 2.

Vertical uprights consist of primary 80 tubes 20 and auxiliary tubes 21, the tubes 21 telescoping within the tubes 20. The primary tubes 20 are provided with clamping bands 22 at their upper ends for causing the ends of the primary tubes 20 to 85 firmly bind upon the tubes 21 for holding the same against accidental shifting. The tubes 20 and 21 are provided with blocks 23 at their outer ends and threaded stems 24 extend from the blocks 23. These stems 24 are 90 pressed through the tubes 11 and 12 of the horizontal supporting members, adjacent the ends of these members, in the manner illustrated in Fig. 5 and in the general arrangement illustrated in Figs. 1 and 2. The knobs 95 25 having nuts 26 are screwed on to the stems 24, since these stems extend through and beyond the tubes 11 and 12, thus holding the uprights in fixed engagement with the horizontal supporting members. 100

When the device is in use for supporting curtains contiguous to a window frame, the tubes 11 and 12 are slipped into suitable receiving portions at the ends of the curtain, in the usual manner. The tubes are then 105 telescoped and thus a substantially rectangular frame is provided, in view of the fact that tubes 20 and 21, constituting the uprights are at this time connected to the tubes 11 and 12. The wall plates 17 may 110 then be moved in desired directions to expand the tubes 11 and 12, thus spacing the

uprights at a greater distance apart, while the horizontal supporting members may be moved away from each other, thus increasing the length of the uprights by retracting 5 the tubes 21 from the tubes 20. The wall plates may then be fixed upon the window frame and the curtains held in a taut condition. Conversely, if it is desired, the tubes 21 may be moved into the tubes 20 and the 10 tubes 12 into the tubes 11, thus reducing the size of the frame. Under any condition, however, regardless of the movement of the tubes it will be seen that when the uprights are connected to the horizontal supporting 15 members the frame will be of a rectangular construction, and may be adjusted to present a device of various sizes desired.

The foregoing description and the drawings have reference to what may be considered 20 the preferred, or approved form of my invention. It is to be understood that I may make such changes in construction and arrangement and combination of parts, materials, dimensions, et cetera, as may prove 25 expedient and fall within the scope of the appended claims.

Having fully described my invention, what I claim as new and desire to secure by Letters Patent is:—

- 30 1. A device of the class described comprising two parallel tubes, each having each end bent at right angles to its body, fastening devices in each extremity thereof, two other parallel tubes having blocks in their extremities, threaded stems projecting from said blocks beyond the ends of these tubes and adapted to be passed through the other tubes, and knobs screwed onto said stems where they protrude.
- 35 2. In a device of the character described comprising a pair of horizontal, tubular telescopic members, the outer ends of the members being bent at right angles to their bodies, a wall plate having a sleeve inserted

Copies of this patent may be obtained for five cents each, by addressing the "Commissioner of Patents, Washington, D. C."

in each extremity, a clamping ring surrounding the extremity and the sleeves of the wall plate, a clamping band surrounding one member where the end of the other is inclosed therein, and a second similar member; combined with upright members 50 having stems projecting through the first named members, and fastening elements on the outer ends of said stems.

3. A device of the character described comprising two horizontal elements, each 55 composed of two telescopic members having their ends bent at right angles to their bodies, wall plates carried in the outer extremities of said ends, and clamping bands inclosing the outer members where the inner ends of the inner members extend therein; combined with two upright members each made in two telescopic parts, clamping bands embracing them where they lap each other, and connections between the outer 60 extremities of these members and the first-named members.

4. A device of the character described comprising horizontal supporting members 70 consisting of telescopic tubes having rearwardly bent ends provided with wall plates, uprights consisting of telescopic tubes having blocks at their ends, stems extending from said blocks and projecting through the tubes of the horizontal supporting members, 75 retaining means engaging said stems for holding said uprights in engagement with said horizontal supporting members, clamping collars carried on said tubes, thus causing the tubes to frictionally bind upon 80 each other, whereby a rectangular frame of adjustable nature is provided.

In testimony whereof I affix my signature in presence of two witnesses.

CHARLES LATHAM.
